[57] ABSTRACT

A carrier easily securable within, and quickly releasable from, a standard pirn or like tubular article having an internal annular flange member within an otherwise hollow tubular body. The carrier is secured by means of a flexible washer which once positioned inside of the annular flange is held in locking engagement with the assistance of an intermediate member abutting the washer to prevent it from flexing. A stabilizing collar secures the flange from the other side thus clamping the flange between washer and collar. The pirn or other article may be released by shifting the washer away from the intermediate supporting member to allow the washer to flex thus permitting the withdrawal of the carrier.

In another embodiment, the carrier is designed to be placed over a carried member having an external flange. The washer flexes during engagement to pass over the flange to the carrying position and is prevented from flexing in the opposite direction by an abutting member until the carrier is released.

CARRIERS FOR PIRNS AND OTHER ARTICLES

BACKGROUND OF THE INVENTION

In knitting mills, yarn processing mills, and the like, it is necessary to carry spooled yarn on pirns during various stages of the preknitting operation. A standard type of pirn is equipped with an internal annular flange near one end which serves as an aid in gripping the pirn, it being important that the spooled yarn is not touched or clamped in any manner. Presently, simple handles having a 90° projecting rod with a bent hooking tip are commonly used to carry pirns; the rod being inserted into the flanged end of the pirn and by means of the hooking tip, the flange is engaged to provide some gripping power. Unfortunately, when using such a device, the hooking tip can easily slide from within the flange, causing the pirns to be dropped when tilted, thus resulting in loss of production time and damaged yarn.

Accordingly, it is an object of the subject invention to develop a carrier for pirns or similar articles which may be easily secured in a carrying position so that the article may be securely carried.

It is a further object of the subject invention to provide a carrier for pirns or similar articles which may be readily engaged, and quickly released from the article with a minimum of effort without sacrificing sure gripping ability.

It is yet another object of the subject invention to provide a carrier for pirns or similar articles which may be securely carried by one hand and in which the carrier may be released from the article by the thumb or a finger of the carrying hand.

In accordance with the above objects, the subject carrier has been developed to be readily insertable into locking engagement within a pirn or similar article and upon actuation of a release lever, may be quickly disengaged from the article. A standard type of tubular pirn has an annular ring or flange within the central bore in close proximity to one end of the pirn which must be present for one of the embodiments of the subject invention.

In this embodiment, the pirn carrier has a body and carrying portion to which a shaft is slideably engaged. The principal parts of the subject invention are disposed about the shaft with a principal component of the device being a leather washer, the center portion of which is firmly secured at a point along the shaft. The washer diameter is greater than the shaft diameter, thus permitting the outer areas of the washer to flex. The carrier has an intermediate or nose member which is circumferentially mounted on the shaft. The washer in its unactuated position is biased to abut against a portion of the nose member which is of less diameter than the washer and in fact is of the approximate inner diameter of the pirn annular flange. A stabilizing collar is circumferentially mounted around a portion of the intermediate member and is biased to a position where the forward part of the collar is approximately coextensive with the washer.

In the embodiment as above described, when the carrier is inserted into the pirn bore, the annular flange of the pirn engages the stabilizing collar and as pressure is applied and the bias of the collar is overcome, the annular flange passes over the leather washer, which because of its flexibility is bent back by the flange. Once the flange has cleared the leather washer, the washer

flexure ceases and when the pressure against the stabilizing collar is eliminated allowing the collar to push the flange back toward the entry end of the shaft, the flange will impact against the washer which is buttressed by the intermediate member to prevent it from flexing in the other direction to release the flange. In this manner the flange is secured between the stabilizing collar and the leather washer is buttressed by the intermediate member.

For use in releasing the connection, the body portion which slideably engages the shaft is provided with an actuating lever which when pressured with a thumb or finger will cause the shaft to be shifted outwardly from the pirn bore. This draws the washer away from the buttressing effect of the intermediate member to allow the washer to flex in a direction opposite from that when the pirn carrier was inserted thus allowing the annular flange to pass over the leather washer to permit the pirn carrier to be withdrawn from the pirn bore.

In another embodiment, the carrier is designed to be used with an object which has an external flange. Such a flange may be attached to a cylindrical member similar to a pirn which might be hollow or solid. The cylindrical member may comprise the entire article or only a part thereof if, for example, it is a neck portion or nub extending from the article.

In this embodiment, the washer is not mounted to the shaft but is secured to an intermediate member which is secured at the shaft end and has a portion with an inside diameter sufficient to allow it to pass over the cylindrical member or receiving portions of the object to be carried. The washer extends inwardly therefrom and has an inner diameter which is less than the outer diameter of the flange to be engaged. A collar which is slideably mounted on the shaft encircles the intermediate member and terminates in a U-shaped portion which serves to buttress the washer against flexing in the manner of the intermediate member of the previously described embodiment which is particularly adapted for pirns.

As the carrier engages the object, the washer flexes as it passes over the flange and once past the flange, it is prevented from flexing in the opposite direction to pass back, by the U-shaped portion of the collar. Thus the object may be lifted with the washer, as buttressed by the collar, resisting the shear forces placed on it by the flange.

The carrier is released as described in the earlier embodiment by means of an actuating lever which causes the shaft to shift which effectively creates a gap between washer and the impact area of the U-shaped portion of the collar, thus creating a gap between the two and permitting the washer to flex and pass over the flange.

The carriers as described in the above two principal embodiments have many applications. For example, along with uses previously described, they may be utilized to carry extremely high temperature items, and which cannot be otherwise touched, objects which are difficult to reach and items which must be handled with the greatest of care.

BRIEF DESCRIPTION OF THE DRAWINGS

FIG. 1 is an isometric view of the carrier and includes a section portion of a standard type of pirn;

FIG. 2 is a partial sectional view of the carrier and pirn being engaged in locking position as the carrier is being inserted;

FIG. 3 is similar to FIG. 2 and shows the carrier locked in engagement with the pirn;

FIG. 4 is an isometric view of the nose cone or intermediate member of the carrier;

FIG. 5 shows the leather locking washer and is viewed along lines 5-5 of FIG. 3;

FIG. 6 is a partial sectional view showing the carrier being released from locking engagement with the pirn;

FIG. 7 is a partial sectional view of another embodiment of the carrier; and

FIG. 8 is a sectional view taken along lines 8-8 of FIG. 7 to illustrate the washer.

DETAILED DESCRIPTION

As can be seen in FIG. 1, a carrier constructed in accordance with an embodiment of the subject invention is shown in position about to be inserted in the end of a pirn where it will become locked in engagement with the pirn which can then be readily lifted, even vertically, without slipping from the grip of the carrier. The carrier may then be readily released when desired as will be described.

More particularly, the pirn carrier 10 has a two part shaft generally designated 11 comprising section 12, and entry section 14. A shaft cap 16 is secured at the opposite end of the shaft from entry end 14. Circumferentially mounted on the shaft is an intermediate or nose member 18 (see also FIGS. 2-4) which has a forward conic portion 20, joining members 22 and a rear portion 24. Circumferentially mounted on the intermediate member 18 is a stabilizing collar 26 which is generally U-shaped in cross section as shown and has a forward face 27. A leather washer 28 is secured to the shaft 11 in a manner which will be described. The rear portion 24 of the intermediate member, with the shaft 11 slideably extending therethrough, is rigidly secured within an aperture of body member 30. A shroud 32 is mounted over the rear portion 24 of the intermediate member and abuts body member 30.

The body member 30 is a right-angled member having an angled slot 34 into which lever arm 36 extends. The lever arm 36 is pivotally secured within the configuration of slot 34 by pin or screw means 38. A handle 40 is mounted to body member 30 by means of bolt 42 upon which actuation lever arm 36 may rest but need not.

The two shaft sections 12 and 14 are secured by an internal screw 43 extending from member 12 into the threaded aperture of section 14 and together secure the leather washer 28 in locking relation. The washer 28 is preferably made of leather but can be constructed of plastic or other substitutes so long as it is flexible. It will be noted that its diameter is considerably greater than the shaft to permit it to flex when pressure is applied. As seen from FIG. 5, the washer has only a small central aperture through which screw 43 extends. Cutaway portions of the washer provide slots for the joining members 22 of the intermediate member 18.

The carrier 10 is designed to engage a pirn 44 of the design shown in FIG. 1 and the succeeding figures. The pirn 44 has a tubular body wall 46 and in the proximity of one end of the bore there is an annular flange-like member 48 which must be a part of the pirn for reasons which will become apparent. It will be noted that the

diameter of the intermediate member 18 is just slightly less than the inner diameter of the annular flange 48.

As best seen in FIG. 3, a first spring member 50 is positioned between leather washer 28 and surface 52 of the rear portion 42 of the intermediate member. A second spring member 54 is positioned within shroud 32 and extends between inner surface 56 of the shroud and rear surface 58 of the stabilizing collar 26. It will be visualized from FIG. 3 that when the pirn 44 is not in engagement with carrier 10 spring means 54 will bias collar 26 forward to where collar inner surface 55 abuts against ridge 57 of the intermediate member 18 so that forward collar surface 27 is approximately coextensive with washer 28. As also can be seen from FIG. 3, body member 30 has inserted at its bottom, screw means 60 to rigidly secure the rear portion 24 of the intermediate member.

With reference to FIG. 2, the first step of inserting the carrier 10 into the bore of pirn or bobbin 44 is shown. As the carrier 10 is being inserted, the forward surface 27 of the stabilizing collar 26 will abut against flange 48 of the pirn. As pressure is applied, the bias from spring member 54 will be overcome causing the stabilizing collar 26 to be pushed away from leather washer 28. It will be noted from FIG. 1 that in the resting position, the outward surface of leather washer 28 is coextensive with the surface 27 of the stabilizing collar. As the pressure of the flange 48 forces the stabilizing collar 26 away from leather washer 28, the flange causes the washer 28 to flex inwardly as shown by the phantom lines in FIG. 2. While the washer member 28 may possess some rigidity, it will be appreciated that it must be flexible enough to bend to allow flange 48 to pass over it. The diameter of the leather washer 28 may be approximately one-quarter of an inch greater than the inner diameter of flange member 48 which as mentioned is approximately the same diameter as the forward section 20 of intermediate member 18. Once the flange has passed over washer 28, the washer 28 will return to its unflexed position only now being on the inside of pirn flange 48. As pressure between the pirn flange 48 and collar 26 is eased, the collar 26 will force the flange 48, relatively speaking, back to a position where the flange 48 abuts against the inner side of leather washer 28 as seen in FIG. 3. Since leather washer 28 is abutted on its outside by forward portion 20 of the intermediate member, flange 48 will not be able to force the washer 28 to the reverse bowed or flexed position from that seen in FIG. 2. Thus, the flange 48 is locked in place between the washer member and the stabilizing collar 26, and the carrier 10 is thus engaged securely in pirn 44. Despite hard pulls on the handle 40, the carrier 10 will remain secured within the pirn 44 until released.

For the carrier 10 to be released from pirn 44, pressure is applied by the thumb of the hand gripping handle 40 at end portion 64 of lever 36. End portion 64 may be equipped with a leather or plastic thumb guard to protect the thumb during the pressure applying movement. As lever 36 is pressed outwardly with respect to handle 40, the lower portion of the lever 66 will be forced outwardly from the body member 30 as the lever pivots about pivot point 38. As this occurs, as is best seen in FIG. 6, the bottom portion 66 of the lever will engage an extended cylindrical surface 68 of cap member 16 thus exerting pressure on the shaft 11 in the direction shown by the arrow on the shaft. The

cap 16 is necessarily securely mounted on shaft 11 and cylindrical portions 68 may be reinforced by a washer or other means to allow the cap 16 to receive the pressure of the lever arm 36. As noted, as pressure is applied, the shaft 11 will be forced in the direction of the arrow pulling with it the washer 28 which is shown in FIG. 6 in its extended position. As the washer 28 shifts, the pinc flange 48 is freed and the carrier 10 may be easily pulled from engagement with the pinc 44. As shown in phantom, the leather washer 28 will eventually be pulled to the position where it will unflex once it is clear of the pinc flange 48. It is at this time that the flange 48 is no longer restrained and disengagement is easily accomplished.

In an alternate embodiment in which the same reference numerals are used to describe parts which are identical to those of the first embodiment, the carrier 69 has been designed to carry a member or object having an external flange which is engaged by the washer member. With respect to FIG. 7, the carried member 20 has a cylindrical projection 72 from which protrudes external flange 74.

The carrier 69 comprises a shaft 76 having a threaded extremity 78 which engages washer holder or intermediate member 80. The washer 82 which is flexible and may be made of leather or substitute material, such as washer 28 previously described, is attached to the member 80 by means of screws 84 or other means. It will be noted that the intermediate member 80 projects out from the shaft 76 in a manner to accommodate the structure of projection 72 for the carried member 70. An abutment member or collar 86 is slideably mounted circumferentially relative to shaft 76 and extends around the outside of member 80. At its extremities there are U-shaped portions 87 which form an impact surface 88 to abut against washer 82 in the locking position. Body member 90 is similar to member 30 previously described except it is rigidly secured to the collar 86. The release lever is substantially as was described with respect to carrier 10 and has a lower end 66 which functions as was previously described impacting against surface 68 of shaft cap 16 when the release lever is actuated.

Spring member 92 is positioned between surfaces of member 80 and collar 86 and serves to bias the washer 82 held by member 80 against the impact portion 88 of the collar 86.

With respect to FIG. 8, the washer member 82 is shown as being secured by four screws 84 to member 80. Notches 94 are provided in the washer 82 to facilitate the flexing of the inner portion when not otherwise constrained.

In operation, the carrier 69 is inserted over the top of projection 72 with the washer 82 passing with relative ease since the surface of member 80 which abuts washer 82 is far enough from the inside portion of the washer 82 not to prevent it from flexing as it passes over the flange 74. Once past the flange, when the carrier 69 is lifted, the washer 82 will impact against the flange member 74 and being unable to flex because of the adjacent impact surface 88, the carrier 69 may be used to lift carried member 70. When the lifting force is released, the washer 82 may slip away from flange 74 but when pressure is resumed, the washer 82 will once again abut securely against flange 74.

When it is desired to release the carrier 69, the release lever is operated in the manner previously de-

scribed with respect to carrier 10 so that its end 66 which is next to shaft 76 will impact against surface 68, pulling the shaft 76 outward with member 80 to overcome the biasing effect of spring 92 thus creating a gap 5 between the impact surface 88 of abutment member 86 and the washer 82. This permits the washer to flex and allows it to pass over flange 74 as the carrier 69 is disengaged.

While particular embodiments of the invention have 10 been shown and described, it will, of course, be understood that various modifications may be made without departing from the principle of the invention. The appended claims are, therefore, intended to cover any such modifications, within the spirit and scope of the 15 invention.

I claim:

1. A carrier designed to securely engage a flanged member comprising:
a shaft;
a flexible washer-type member, a portion of which is fixed securely relative to said shaft and which when in the secured position abuts against the flange;
a member slideably mounted on said shaft which in the secured position has a portion which abuts against a portion of said washer-type member to prevent it from flexing thus securing the flange; and
means communicating with said shaft to separate said slideable member from the portion of said washer-type member to which it abuts in the secured position thereby allowing said washer-like member to be flexed and the flange disengaged.

2. The carrier of claim 1 in which the flanged member comprises a projection with an external flange and the carrier further comprises an intermediate member 35 secured to said shaft, said intermediate member having a portion which has an inner diameter greater than the outer diameter of said flange and having said washer-type member secured thereto with an inner diameter that is less than the outer diameter of said flange.

3. The carrier of claim 2 in which a spring extends between a surface of said slideably mounted member and a surface of said intermediate member and when said separation means is actuated said surfaces are drawn closer together relatively as said washer-type member 40 is drawn apart from said portion of said slideable member which abuts against said washer-type member in the secured position.

4. The carrier of claim 3 including a body member and handling means which are secured to said slideable member so that said shaft when actuated by said separation means moves relative to said body member and handling means which are held during actuation.

5. The carrier of claim 1 wherein said flanged member comprises a hollow tubular member with an internal flange having an inner diameter which is less than said washer-type member and said carrier further comprises a spring biased U-shaped member, which is engaged by said flange as said carrier engages said tubular member and which assists in securing said flange.

6. The carrier of claim 5 wherein in the secured position said flange is secured between said washer-type member as abutted by said slideable member and said U-shaped member.

7. A portable carrier adapted to be inserted into locking engagement within a pinc which has an inner annular flange in which the carrier comprises:
a body portion;

a shaft secured to said body member distant from the forward entry end of said shaft;
 an intermediate cylindrical member circumferentially mounted on the shaft having forward and rear portions; 5
 a flexible washer member circumferentially connected to the shaft in juxtaposition to the forward portion of said intermediate member;
 a cylindrical stabilizing collar generally U-shape in cross section mounted in part around the rear portion of said intermediate member; 10
 a first spring means circumferentially disposed around said shaft and extending between said washer member and the rear portion of said intermediate member to bias said washer member against said forward portion of said intermediate member; 15
 a second spring means circumferentially disposed around said rear portion of said intermediate member and positioned between said body and said collar to force said collar to the approximate position 20

of said washer member, whereby when the annular flange of a pin is pressed against said collar, the bias of said second spring means may be overcome allowing said collar to be pushed to the rear of said washer member as said washer member flexes to allow said annular flange to pass over it, said flange being secured between said collar and said washer member as the pressure against said collar is released, said washer member having returned to an unflexed position abutting against the forward portion of said shaft; and
 actuating means connected to said body portion operable to shift said shaft whereby the bias of said first spring is overcome and said washer member will move away from said forward part of said intermediate member thus allowing said washer member to be flexed in the opposite direction from that when the pin was inserted thereby allowing said carrier to be removed from said pin as said flange passes over said flexed washer member.
